UNITED STATES PATENT OFFICE.

ERNST FRIEDRICHs, OF BARMEN, GERMANY.

UNLOADER AND STARTER FOR COMPRESSORS AND PUMPS.

1,073,801.

Specification of Letters Patent. Patented Sept. 23, 1913.

Application filed December 7, 1910. Serial No. 596,037.

To all whom it may concern:

Be it known that I, ERNST FRIEDRICHs, a subject of the King of Prussia and German Emperor, and a resident of 8 Ge-
5 markerstrasse, Barmen, Germany, have in-
vented new and useful Improvements in
Unloaders and Starters for Compressors
and Pumps, of which the following is a
specification, reference being had therein to
10 the accompanying drawings.

This invention has reference to a self-
acting starting device for the driving mech-
anism of compressors and pumps under pres-
sure, and it is particularly intended to avoid
15 having the motor for the operation of the
compressor or pump starting under load at
any time, the motor engine being on the
contrary only connected to the compressor,
after it has reached its normal number of
20 revolutions.

The arrangement, herein described, can
be used both for the well known starters of
electromotor engines as well as for specially
constructed starters of electric operating ma-
25 chines, and it can also be used advanta-
geously for belt driving.

Aside from the purpose indicated, the sub-
ject matter of the invention presents the
additional advantage, that the starting de-
vice can be actuated even in the case of any
30 leakages in the compressed air conduit by
the combination with additional safety de-
vices and without irregularities.

The invention is shown in several embodi-
35 ments on the accompanying drawing, in
which—

Figure 1 is the starting device for com-
pressors, driven by electric motors, and at
the moment of cutting the motor out of
40 circuit; Fig. 2 shows the same device with
the motor switched into circuit again. Fig.
3 shows diagrammatically the wiring of cir-
cuit connections, corresponding to the ar-
rangement of Figs. 1 and 2. Fig. 4 is a
45 vertical section through another modifica-
tion, suitable for ordinary electric starters.
Fig. 5 is a section through another modifi-
cation, suitable for compressors with belt
driving.

50 The essential feature of the invention re-
sides in the fact, that by means of the pres-
sure governor which is mounted in the com-
pressor conduit, the switch for the motor
engine is operated either directly or indi-
55 rectly and at the same time the arrangement

is such, that the air conduit for the com-
pressor suction pipe is opened, only after
the starter has passed the last contact. This
contact causes the load to be taken off from
the conduit leading to the starting valve 60
of the compressor by means of a solenoid or
the like, and by means of a valve, a multiple
way cock or some similar controlling device
arranged in the operating conduit so that the
said starting valve is connected to the at- 65
mosphere, and the load is therefore put on
the motor.

In the embodiment of the invention,
shown in Figs. 1-3, the switching into cir-
cuit of the motor starter is effected by a 70
mercury reversible switch *t* (Fig. 3) and
the movement of the motor starter is effected
by a special auxiliary starter in the well
known manner, when the switch arm *o* has
reached the last switching contact, so that 75
the number of revolutions of the motor
which operates the compressor, is normal,
another additional contact which does not
interfere with the further movement of the
motor engine, is operated, by means of 80
which current is fed to the solenoid *k*, in-
cluded in a shunt of the main circuit, and
the core of which actuates a controlling
slide *e*, *e*¹ for the conduit *g* which leads to
the starting valve of the compressor, and 85
by this means the compressed air from be-
low the valve *i* is free to escape by way of
the said valve *e*, *e*¹, and the pressure
governor *b*. Then, the compressor will be
able to suck in another supply of fresh air 90
and thereby, it puts the load on the electric
motor which is already running at its full
capacity.

In Fig. 1 of the drawing, *b* is the pressure
governor, *a* is the corresponding controlling 95
piston the piston rod of which is connected
to the main contact. The conduit *c* of the
pressure governor is connected to the con-
duit from which the air is taken off for con-
sumption. By means of the counter conduit 100
d the pressure governor *b* is connected to a
double auxiliary slide valve *f* the slide *e*, *e*¹
of which connects the conduit *g* which leads
to the compressor starting valve or to its
main piston *h*, alternately with the auxiliary 105
conduits *d* and *l*, the connection with the
conduit *d* being effected, when there is a
minimum of pressure in the working con-
duit *c*, while the connection with the conduit
l is effected at an increase of pressure in the 110

working conduit up to the adjustable maximum of pressure.

The mode of operation is as follows:

When the pressure in the conduit has risen up to the admissible maximum of pressure, this causes the piston a of the pressure governor b to be raised to its highest position (Fig. 1). By means of the rod system, connected to the piston a , the main switch t of the electric motor operating the pump, is reversed, the motor being thereby arrested. Then the air pressure from the conduit c is admitted below the piston a by means of the conduit d , and through the conduit d it passes below the part e^1 of the slide e , e^1 of the auxiliary valve f , and through the annular space e^2 of the slide e , e^1 , it is admitted into the conduit g and below the piston h of the compressor suction valve i . The compressor will then run idle. By the reversing of the main switch t for the electric motor however, the solenoid k which operates the slide e , e^1 is deenergized and allows the slide e , e^1 to drop (position shown in full lines in Fig. 1). In this position of the slide e , e^1 the compressed air under its full pressure flows through the conduit l and through the annular space e^2 of the slide e , e^1 and through the conduit g below the piston h of the compressor suction valve i , and thereby maintains this valve in the raised position. In consequence thereof both the action of motor as well as the compressor is arrested. Inasmuch as the compressor has now ceased to work and does not produce any new quantities of compressed air, the pressure in the conduit c will have gone down to the minimum in a short time by the consumption of compressed air. In consequence of this minimum however, the piston a descends, and it finally assumes the position, shown in Fig. 2 of the drawing, so that the air would escape to the outside from the conduit d , and would release the suction valves, causing them to operate, were it not for the presence of the auxiliary valve f which keeps the air conduit g , d still closed, as the slide e , e^1 still maintains its position indicated in full lines in Fig. 1 of the drawing. In this lower position of the governor piston a the main switch is again in the operating position, so that the electric motor begins to move, though the suction valve i is still prevented from operating, in view of the fact, that the slide e , e^1 as indicated above, is still maintained in its lower position (shown in Fig. 1). Only after the starter has reached the last contact, the auxiliary contact (p in Fig. 3) for the solenoid k of the valve f is closed, the solenoid k is energized, and the slide valve e , e^1 is raised, so that the pressure under the piston h disappears in consequence of the connection of the conduits g , and d with the outside. The suction valve i is thereby caused to drop

back upon its seat and air can be sucked in again through the tubing v from the outside.

The mode of operation of the modification, shown in Fig. 4 is as follows: The piston o contained in the pressure governor k is forced into its highest position, when the pressure is at its maximum by the compressed air, admitted from the air pressure conduit through the pipe p . When the air pressure is reduced by the consumption of air below a certain limit, for which the pressure governor k can be adjusted by the sliding weight q , the piston o of the pressure governor is also lowered, and assumes the lower position, indicated in Fig. 5. In this position of the piston o^1 the connecting pipe g , h and in consequence thereof that part of the interior of the cylinder b below the piston u are connected to the outside air, and both pistons d and u , are depressed into their lower positions d^1 and u^1 by the air pressure acting upon the piston d . By means of the rack bar r which constitutes the middle of the piston rod c and by the toothed wheel s engaging with the rack bar, the rectilinear movement of the two pistons d and u is converted into a rotating movement. By means of a sprocket wheel or a rope pulley or sheave t mounted on the shaft of the toothed wheel, the rotary movement is then transmitted to the motor starter L , as shown in Fig. 4 or to a belt shifter F , shown in Fig. 5.

In the mode of operation, herein described the compressor would be operated, and the feeding of air to the receiver would commence, but for the auxiliary valve f which in the position which its slide valve e , e^1 assumes in Fig. 4 of the drawing, retains the compressed air in the connecting pipe v^1 , so as to act below the piston w , and locks the blow off valve m in its highest position. Only after the rack bar r has moved the two-armed lever z and consequently the piston e , e^1 of the auxiliary valve f to its upper position, indicated in Fig. 5 of the drawing by means of the guide block y connected to the arm x of the piston rod c which is effected shortly before the rack bar r has reached its lowest position, the air, inclosed below the piston w of the blow off valve m , is free to escape through the pipes v , g and h and by way of the pressure governor k , and by way of the piston which is then in its position, indicated at o^1 in Fig. 5 of the drawing, the air escaping to the outside, while the piston w , and the blow off valve m are lowered into their positions m^1 and w^1 shown in Fig. 5; the air from the compressor is thereby cut off from the outside air, and is compelled to flow into the compressed air working conduit N . Hence the compressor is now under load. As soon as the desired maximum of pressure has

been reached, the piston o of the pressure governor k is raised into its upper position, indicated in Fig. 4 of the drawing; the compressed air passes through the connecting pipe h , and by way of the piston e, e^1 which is in its raised position and operates the auxiliary valve f , and through the pipe v , below the piston w of the blow off valve m , so that these two pistons are raised, and the load is taken off the compressor, while the air from the compressor is now free to escape to the outside through the blow off valve m which is now opened. At the same time, compressed air passes through the connecting pipe g under the piston u^1 which is shown in Fig. 5 in its depressed position.

In the case of equal air pressures acting upon the two pistons u, u^1 in opposite directions, the lower piston u^1 on account of its greater surface will overcome the total pressure of the piston d^1 , and both pistons will be moved into their upper positions d and u indicated in Fig. 4 of the drawing. This movement is transmitted to the motor starter L of Fig. 4, or to the belt shifter F of Fig. 5 of the drawing in the manner above described by means of the piston rod c , the rack bar r , the toothed wheel s and the sprocket wheel or the sheave or pulley t , the motor and the compressor being stopped in the latter case. In consequence of the movement just described, however, the arm x which is secured to the rack bar r and the guide block y are moved upward until the guide block, shortly before it has reached its upper position, indicated in Fig. 4 moves the slide valve e, e^1 of the auxiliary valve f by means of the two-armed lever z into the lower position, shown in Fig. 4 of the drawing. By means of this position of the auxiliary valve slide e, e^1 the compressed air under the piston w of the blow off valve m is prevented from returning through the pipe v^1 and through the blow off valve m in its open position.

In order to avoid too rapid, premature dropping down of the blow off valve m upon its seat by any possible leakages of the pipe v^1 or of its screw threaded fittings, or by any leakages of the slide valve e, e^1 of the auxiliary valve f and of the piston w of the blow off valve m , and in order to avoid any consequent danger of the starting of the compressor under load, provision is made, that compressed air is always made to pass through the pipe i and through the slide e, e^1 of the auxiliary valve f in its lowest position and through the pipe v so that the air gets under the piston w of the blow off valve m , and the valve m is maintained raised in its upper position.

In Fig. 4 the self acting device is shown in connection with a starter L for an electro motor, driving the compressor.

In order to adapt the herein described

starting device to the usual rule, observed in the starting of electro motor engines, that is to say, "switch in slowly, cut out quickly," the lower extension of the rack bar r is provided with a piston rod A , on which is mounted the piston B of any well known cushioning or braking device. The piston B is provided with holes C which are covered up by adjustable flat springs D on the lower side of the piston B . The piston B moves in the cylinder E which is filled with oil, together with the pistons d and u and their common piston rod c , and in the same direction, in such a manner that upon the descent of the piston B , that is to say of the starter of the motor engine the oil is forced out through the holes C of the piston B the free section of which has been reduced by adjustment of the flat springs d , so that the motion of the piston B , and the adjustment of the starter and of the motor are retarded. When the piston B is moving upward, the oil raises the flat springs D , and flows through the holes c into the lower space of the cylinder E , and cuts out the starter and the motor with a quick motion.

In Fig. 5 the self acting starting device is shown in connection with a belt shifter or shipper lever. F is the belt shifter, G is the pulley of double width, and mounted upon the driving shaft, H is the loose pulley upon the shaft of the driven compressor, J is the fast pulley. The operation of the belt shifter or shipper lever F is effected by means of chains, ropes or by a system of levers from the sheave or the sprocket wheel t .

The regulation of the velocity of the shifting movement is effected both by a suitable ratio of the surfaces of the two pistons d and u as well as by regulating the admission and the discharge of air by the adjustable cock K which depends upon the difference of capacity of the cylinders a and b .

In the case of heavy machinery the air for the regulation of the velocity is replaced by oil which is introduced into the space between the pistons d and u .

Having now described my invention what I claim as new, is:

1. In an apparatus of the class described, the combination of a conduit connected with the compressor, a valve in the conduit, a piston and cylinder device connected with the valve for opening and closing the same, a pressure governor connected with the discharge side of the compressor, and an auxiliary valve for connecting the pressure-responsive device to the atmosphere when the pressure on the governor is at a predetermined minimum and for connecting the said device with the discharge side of the compressor when the pressure acting on the pressure governor is above a predetermined maximum.

2. In an apparatus of the class described, the combination of a conduit connected with the compressor, an unloading valve for opening the conduit to the atmosphere, a 5 pressure-responsive device for controlling the valve, a pipe leading to the said device, an auxiliary valve connected with the pipe, a pressure governor, a connection between the discharge side of the compressor and the governor and the auxiliary valve whereby the output pressure of the compressor acts on the governor and through the auxiliary valve on the first-mentioned valve, and a connection between the pressure 10 governor and auxiliary valve for permitting the pressure in the said pipe to escape to the atmosphere when the pressure acting on the governor is below a predetermined minimum.
- 15 3. The combination of an unloading valve, a pressure-responsive device controlling the same, an auxiliary valve in the form of a cylinder and a double-headed piston, a connection between the cylinder and said pressure-responsive device, a conduit connected with the discharge side of the compressor and the said cylinder and controlled by one head of the piston, a pressure 20 governor also connected with the discharge side of the compressor and including a movable element, and a connection between the pressure governor and said cylinder, said connection being controlled by the movable element of the pressure governor and by the other head of the piston of the auxiliary 25 valve.
- 30 4. The combination of an unloading valve, a pressure-responsive device connected therewith, an auxiliary valve consisting of a cylinder and a double-headed piston, a connection between the cylinder and said device and controlled by one head of the piston, a conduit connected with the discharge side of the compressor and connected 35 with the cylinder and controlled by the same head of the piston that controls the said connection, a pressure governor including a piston and cylinder, a connection between the pressure governor cylinder and the discharge side of the compressor, and a connection between the auxiliary valve cylinder and the pressure governor cylinder and controlled by the other head of the said piston and also by the piston of the pressure 40 governor whereby the pressure on the pressure-responsive device may escape through the auxiliary valve and said last-mentioned connection when the pressure on the governor is below a predetermined minimum, a reciprocating element for actuating the auxiliary valve, and a differential piston motor connected with the said element having its portion of smaller area connected with the discharge side of the compressor and its portion of larger area connected with the said connection between the pressure 45 governor and auxiliary valve.
- 50 5. The combination of an unloading valve, a pressure-responsive device connected therewith, an auxiliary valve consisting of a cylinder and a double-headed piston, a connection between the cylinder and said device and controlled by one head of the piston, a conduit connected with the discharge side of the compressor and controlled by the other head of the said piston and also by the piston of the pressure 55 governor whereby the pressure on the pressure-responsive device may escape through the auxiliary valve and said last-mentioned connection when the pressure on the governor is below a predetermined minimum.
- 60 6. The combination of an unloading valve, a pressure-responsive device connected therewith, an auxiliary valve consisting of a cylinder and a double-headed piston, a connection between the cylinder and said device and controlled by one head of the piston, a conduit connected with the discharge side of the compressor and connected 65 with the cylinder and controlled by the same head of the piston that controls the said connection, a pressure governor including a piston and cylinder, a connection between the pressure governor cylinder and the discharge side of the compressor, a connection 70

between the auxiliary valve cylinder and the pressure governor cylinder and controlled by the other head of the said piston and also by the piston of the pressure governor whereby the pressure on the pressure-responsive device may escape through the auxiliary valve and said last-mentioned connection when the pressure on the governor is below a predetermined minimum, a reciprocatory element for actuating the auxiliary valve, a differential piston motor connected with the said element having its portion of smaller area connected with the discharge side of the compressor and its portion of larger area connected with the said connection between the pressure governor and auxiliary valve, a motor starter connected with the reciprocatory element, and means for retarding the movement of the element in one direction only.

8. The combination of an unloading valve for a compressor, a pressure governor

connected with the discharge side of the compressor, a pressure-responsive device controlling the said valve, an auxiliary valve between the pressure governor and pressure-responsive device for controlling the latter, a reciprocatory element, a connection between the said element and auxiliary valve for actuating the latter, and a pneumatic motor having a differential area piston connected with the said element, a connection between the pressure governor and side of the piston of larger area, and a connection between the discharge side of the compressor and the side of the piston of smaller area, and a motor starter operated by the said element.

In testimony whereof I affix my signature in presence of two witnesses.
